DESIGN FOR A BROOCH OR SIMILAR ARTICLE

Norma E. Jansen, Oakland, Calif.

Application February 7, 1946, Serial No. 126,352

Term of patent 3½ years

(Cl. D45—19)

To all whom it may concern:

Be it known that I, Norma E. Jansen, a citizen of the United States and a resident of Oakland, county of Alameda, and State of California, have invented a new, original, and ornamental Design for a Brooch or Similar Article, of which the following is a specification, reference being had to the accompanying drawing, forming part thereof.

I claim:

The ornamental design for a brooch or similar article, substantially as shown.

NORMA E. JANSEN.
